UNITED STATES PATENT OFFICE.

ROBERT H. McDONOUGH, OF HAMTRAMCK, MICHIGAN.

COMBINATION-LOCK.

1,249,440.

Specification of Letters Patent. Patented Dec. 11, 1917.

Application filed November 10, 1916. Serial No. 130,509.

To all whom it may concern:

Be it known that I, ROBERT H. McDONOUGH, a citizen of the United States of America, residing at Hamtramck, in the county of Wayne and State of Michigan, have invented certain new and useful Improvements in Combination-Locks, of which the following is a specification, reference being had therein to the accompanying drawings.

The invention relates to combination locks and has more particular reference to a construction adapted for use upon door knobs to control the operation of the latch-bolt. The invention comprises various novel features of construction as hereinafter set forth.

In the drawings:

Figure 1 is a vertical section in the plane 20 of the axis of the knob;

Figs. 2, 3 and 4, are cross-sections on lines $x-x$, $y-y$, and $z-z$ Fig. 1;

Figs. 5 and 6 are views similar to Fig. 2 showing different positions of adjustment; 25 and

Fig. 7 is an elevation from the reverse side of Figs. 2 to 6.

A is a door and B is the lock located in a recess or mortise therein. C is the inner 30 knob, D the outer knob and E the latch bolt operated by said knobs through the medium of rock-arms C' D'.

For locking the bolt E from actuation by the knobs it is provided with a series of 35 pawls or tumblers F, which are pivotally attached thereto and are adapted to engage with a stationary locking shoulder or detent F'. When any one of the pawls is thus engaged the latch-bolt E will be held from 40 movement and will therefore lock the door. To release the bolt it is necessary to disengage all of the pawls, which is accomplished by mechanism constructed as follows:

G G' G², etc., are cams, which are sleeved 45 upon the inner shank H which secures the two knobs to each other. Each of these cams is provided with a pointed projection I for engaging a coöperating pointed projection J on the corresponding pawl, the 50 arrangement being such that the pawl will be disengaged only when the two points are in registration. The cams are connected to each other by a lost-motion engagement, such that they may be successively operated 55 to disengage their corresponding pawls by an oscillatory adjustment of a common actuating member. This actuating member is

preferably a knob K located in a recess in the end of the outer knob D and provided with a graduated annular portion L which 60 may be rotatively adjusted in relation to an index mark. The knob K is connected to a sleeve M surrounding the shank H and this sleeve in turn is keyed or otherwise secured to one of the cams G. Thus whenever the 65 knob K is revolved the cam G will be actuated thereby, and as the lost-motion is taken up the other cams G' G², etc., will be successively revolved. Upon reversing the direction of rotation the lost-motion must be 70 again taken up, and thus it is possible to successively set the cams in any predetermined position if the index combination is known.

The inner knob C is provided with means 75 for simultaneously disengaging all of the pawls, which as shown comprises a rockable member N having a bar O extending beneath the pawls. The member N is also provided with a cam portion N' for engaging 80 a coöperating cam portion P upon the rock-arm C', and sufficient lost-motion is provided in the portion of this rock-arm for retracting the bolt E to permit of the previous operation of the cams P and N', 85 whereby the bar will lift all of the pawls F. This construction permits of retracting the latch-bolt E whenever the inner knob C is turned while the outer knob can only operate the bolt when the cams G are all in registration and in a position to lift the pawls F. The cams G are held from accidental displacement by friction devices, preferably 90 spanners Q which engage cylindrical hubs R on the cams and which are anchored by 95 engagement with a rod S. The hubs R preferably have segments thereof cut away to engage with coöperating segments of the adjacent cams, these forming the lost-motion connection by which the cams are successively set. 100

In operation whenever it is desired to open the door from the outside, the knob K is manipulated according to a predetermined combination, thereby successively 105 setting the cams G in registration and disengaging the pawls F. When all of the pawls are released the knob D may be turned which will cause the rock-arm D' to retract the latch-bolt, the pawls traveling 110 over a guide-way T. One or more of these pawls is provided with a projection U, which as the bolt is retracted engages the corresponding cam G, and throws it out of

its set position. Thus when the bolt is again projected by a spring V or other suitable returning means, the pawl will be permitted to drop into engagement with the shoulder 5 F', preventing further retraction of the bolt until the combination is again reset.

The lock is preferably provided with means for holding the latch-bolt from projection to its locking position, such as the 10 cam W, which when turned in one position will engage a shoulder W' on the bolt, allowing the latter to project sufficiently to function as a door latch, but preventing a complete projection such as will allow the 15 pawls to have locking engagement with the shoulder F'. This cam may be operated by a suitable knob or lever located on the inside of the door.

It will be readily understood that 20 concealment of the cams is essential to prevent unauthorized actuation of the same to their positions for raising the tumblers F and the location of the parts within the casing B supplies the desired concealment.

25 What I claim as my invention is:—

1. The combination with a locking bolt and means for retracting the same, of a series of pawls carried by said bolt, each adapted to lock the bolt from retraction, a 30 series of concealed cams for respectively actuating said pawls to release the bolt, and lost-motion connecting means between said cams by which they may be successively actuated according to a predetermined combination 35 nation to release all of said pawls.

2. The combination with a bolt and means for retracting the same, of a series of pawls pivotally attached to said bolt, a detent for engaging said pawls to hold the bolt from 40 retraction, a series of concealed cams for respectively lifting said pawls out of engagement with said detent, operating mechanism by which said cams may be successively positioned according to a predetermined combination 45 to lift all of said pawls and permit the retraction of said bolt, and means for automatically throwing the combination upon the retraction of the bolt.

3. The combination with a locking bolt 50 and means for retracting the same, of a series of pawls carried by said bolt, a detent for engaging said pawls to lock the bolt from retraction, a rotatively adjustable member, a series of cams sleeved upon said 55 member and respectively engageable with said pawls, each being adapted to lift its corresponding pawl out of engagement with said detent, lost-motion connections between said cams and said rotative member, by 60 which the cams may be registered or set in accordance with a predetermined combination to disengage all of said pawls from said detent, and means automatically operating upon the retraction of the bolt to throw said 65 cams out of registration.

4. The combination with a locking bolt, of a knob for retracting the same, a series of pawls and a coöperating detent for holding said bolt from retraction, a rotative member carried by said knob, and mechanism operated by said rotative member according to a predetermined combination for disengaging said pawls from said detent to permit the retraction of said bolt by said 70 knob. 75

5. The combination with a locking bolt, of a knob for retracting the same, a series of pawls carried by said bolt, a detent for engaging said pawls to hold said bolt from retraction, a series of cams for respectively 80 disengaging said pawls from said detent, and a rotative member carried by said knob having a lost-motion engagement with said cams, whereby the manipulation of said rotative member according to a predetermined 85 combination will disengage all of said pawls and permit retraction of said bolt by said knob.

6. The combination with a locking bolt, of a knob for retracting the same, a series 90 of pawls carried by said bolt, a detent for engaging said pawls to hold said bolt from retraction, cams arranged concentric with said knob for respectively actuating said pawls to disengage the same from said detent, and a second knob rotatively mounted on said first-mentioned knob and having a lost-motion connection with said cams, whereby they may be successively actuated according to a predetermined combination 95 100 to disengage all of said pawls and permit retraction of said bolt by said knob.

7. The combination with a locking bolt, of a knob for retracting said bolt, a series 105 of pawls, each of which is adapted to hold said bolt from retraction, cams coaxially arranged with said knob for respectively actuating said pawls to disengage the same, a second knob mounted upon and independently rotative in relation to said first-mentioned knob, lost-motion connections between said second knob and said cams in series, whereby the manipulation of said second knob in accordance with a predetermined combination will set said cams to release 110 115 said pawls, independent means for simultaneously disengaging all of said pawls, and an oppositely-arranged knob connected to actuate said second disengaging means and to retract said bolt. 120

8. The combination with a locking bolt and means for retracting the same, of a series of pawls each adapted to lock the bolt from retraction, a series of concealed cams for respectively actuating said pawls to release the bolt, and lost-motion connecting means between said cams by which they may be successively actuated according to a predetermined combination to release all of said 125 130 pawls. 130

9. The combination with a locking bolt, of a series of pawls, each adapted to lock the bolt from retraction, means for successively disengaging the pawls, and independent means for simultaneously actuating the pawls to release the bolt and permit retraction thereof. 5
10. The combination with a locking bolt, of a series of devices for independently locking the bolt from retraction, means for successively disengaging said devices, and independent means for simultaneously actuating said devices to release the bolt and permit retraction thereof. 10
- 15 11. The combination with a locking bolt, of a series of pawls, each adapted to lock the bolt from retraction, a series of concealed cams for respectively actuating said pawls to release the bolt, actuating means for the cams, and means for simultaneously disengaging the pawls. 20
- 25 12. The combination with a locking bolt, of a series of pawls, each adapted to lock the bolt from retraction, a series of concealed cams for respectively actuating said pawls to release the bolt, a lost-motion connecting means between said cams by which they may be successively actuated according to a predetermined combination to disengage all of said pawls, and means for simultaneously disengaging the pawls. 30
- 35 13. The combination with a locking bolt, of a plurality of devices, each adapted to lock the bolt from retraction, a knob for reTRACTING the bolt, a rotatively adjustable member carried by the knob, and means for actuating said devices from the rotative member to successively disengage the same and permit retraction of the bolt. 40
- 45 14. The combination with a locking bolt, of a plurality of devices for locking the bolt from retraction, means for successively disengaging said members to allow retraction of the bolt, and a common means for first simultaneously disengaging said members and subsequently retracting the bolt. 50
- 55 15. The combination with a locking bolt and means for retracting the same, of a series of pawls, each adapted to lock the bolt from retraction, a series of concealed cams for respectively actuating the pawls to release the bolt, means for holding said cams from accidental displacement, and lost-motion connecting means between said cams by which they may be successively actuated according to a predetermined combination to release all of said pawls. 60
- 65 16. The combination with a locking bolt and means for retracting the same, of a series of pawls for respectively locking the bolt from retraction, a series of concealed cams for respectively actuating said pawls to release the bolt, and resilient members respectively frictionally engaging the cams preventing accidental displacement thereof, 65
- and means for successively actuating the cams according to a predetermined combination to release all of the pawls. 70
17. The combination with a locking bolt, of a series of devices for respectively locking the bolt from retraction, a knob at one side of the bolt for retracting the same, means associated with said knob for successively disengaging said devices from their positions resisting retraction, and an aligned knob at the other side of the bolt for first disengaging said devices and subsequently retracting the bolt. 75
18. The combination with a locking bolt and means for retracting the same, of a pawl pivotally attached to said bolt and a guide member for supporting said pawl during sliding motion of the bolt, said guide member and pawl having shoulders interengageable to resist retraction of the bolt. 80
- 85 19. The combination with a locking bolt and means for retracting the same, of a pawl pivotally attached to said bolt, a guide member for supporting the rear extremity of said pawl during sliding motion of the bolt, said guide member functioning further as a detent and the free extremity of the pawl being formed with a shoulder engageable with said detent to resist retraction of the bolt. 90
- 95 20. The combination with a locking bolt, of a series of pawls pivotally attached to said bolt, a member forming a support for the free extremities of said pawls and forming also a detent for interlocking with said pawls to resist retraction of the bolt and means for successively disengaging said pawls from the detent. 100
- 105 21. The combination with a locking bolt, of a series of pawls pivotally attached to said bolt, a detent for engaging said pawls to hold the bolt from retraction, means for successively disengaging said pawls from the detent and independent means for simultaneously disengaging the pawls therefrom. 110
- 115 22. The combination with a casing, of a locking bolt therein, a series of devices attached to the bolt for independently locking the same from retraction, a member carried by the casing engageable with said devices to resist retraction of the bolt, means for successively disengaging said devices from said member and independent means for simultaneously disengaging said devices from said member. 120
- 125 23. The combination with a locking bolt, of a plurality of pawls pivotally attached thereto, a detent engageable with said pawls to resist retraction of the bolt, means for successively disengaging said pawls to allow retraction of the bolt and a common means for first simultaneously disengaging the pawls and subsequently retracting the bolt. 130
24. The combination with a bolt and means for retracting the same, of a series

- of pawls each adapted to lock the bolt from retraction, a series of concealed cams for respectively disengaging the pawls, operating mechanism by which said cams may be 5 successively positioned according to a predetermined combination to disengage all of said pawls and permit retraction of the bolt, and means for automatically throwing the combination upon the retraction of the bolt.
- 10 25. The combination with a locking bolt and means for retracting the same, of a series of pawls each adapted to lock the bolt from retraction, a rotatively adjustable member, a series of cams sleeved upon said 15 member and respectively engageable with said pawls each being adapted to disengage its corresponding pawl, lost motion connections between said cams and said rotative member by which the cams may be registered or set in accordance with a predetermined combination to disengage all of said pawls, and means automatically operating 20 upon the retraction of the bolt to throw said cams out of registration.
- 25 26. The combination with a locking bolt, of a knob for retracting the same, a series of pawls pivotally attached to said bolt, a detent engageable with said pawls to hold the bolt from retraction, a rotative member 30 carried by said knob and mechanism operated by said rotative member according to a predetermined combination for disengaging said pawls from said detent to permit retraction of the bolt by said knob.
- 35 27. The combination with a locking bolt, of a knob for retracting the same, a series of pawls respectively adapted to lock the bolt from retraction, a series of cams for respectively actuating said pawls to release 40 the bolt and a rotative member carried by said knob having a lost motion engagement with said cams whereby the manipulation of said rotative member according to a predetermined combination will disengage all 45 of said pawls and permit retraction of the bolt by said knob.
- 50 28. The combination with a locking bolt, of a knob for retracting the same, a series of pawls each adapted to lock the bolt from retraction, cams arranged concentric with said knob for respectively actuating said pawls to release the bolt and a second knob rotatively mounted on said first mentioned knob and having a lost motion connection with said cams whereby they may be successively actuated according to a predetermined combination to disengage all of said pawls and permit retraction of the bolt by said knob.
- 55 60 29. The combination with a locking bolt and means retracting the same, of a series of pawls each adapted to lock the bolt from retraction, a rotatively adjustable member,
- a series of cams sleeved upon said member and respectively engageable with said pawls, 65 each being adapted to actuate its corresponding pawl to release the bolt therefrom, and lost motion connections between said cams and said rotative member by which the cams may be registered or set in accordance with a predetermined combination to disengage all of said pawls.
30. The combination with a locking bolt, of a series of pawls each adapted to lock the bolt from retraction, a series of cams for 75 respectively actuating said pawls to release the bolt, actuating means for the cams, and means for automatically throwing the combination upon the retraction of the bolt.
31. The combination with a locking bolt, 80 of a series of pawls each adapted to lock the bolt from retraction, a series of cams for respectively actuating said pawls to release the bolt and actuating means for the cams, said pawls having shoulders engageable 85 with the cams upon retraction of the bolt for automatically displacing them from their pawl engaging positions.
32. The combination with a bolt, of means for retracting the bolt, means associated 90 with said bolt to lock the same in its fully projected position, and a member independent of the retracting means adjustable for engagement with said bolt in its projected position to prevent full projection thereof. 95
33. The combination with a casing, of a bolt therein, means for retracting the bolt, means associated with said bolt to lock the same in fully projected position, a cam adjustable to engage a shoulder of said bolt 100 in a partially projected position thereof to prevent full projection of the bolt, and actuating means for said cam exterior to the casing, and independent of the means for retracting the bolt. 105
34. The combination with a bolt, of means for retracting the bolt, a series of pawls each adapted to lock the bolt from retraction in its fully projected position, and a member independent of the retracting means 110 adjustable to be engaged with said bolt in a partially projected position thereof to prevent full projection of the bolt.
35. The combination with a bolt, of a plurality of pawls pivotally attached thereto, a member forming a support for the free extremities of said pawls during sliding motion of the bolt and forming a detent for interlocking with said pawls when the bolt is fully projected and a member adjustable to engage said bolt in a partially projected position thereof to prevent its 115 full projection. 120
- In testimony whereof I affix my signature.
- ROBERT H. McDONOUGH.
